(57) **CLAIM**

We claim the ornamental design for the packaging container,
as shown and described.

DESCRIPTION

FIG. 1 is a front and top perspective view of the packaging container of the present invention;

1 Claim, 12 Drawing Sheets

FIG. 2 is a rear and bottom perspective view of the packaging container shown in FIG. 1;

FIG. 3 is a front view of the packaging container shown in FIG. 1;

FIG. 4 is a rear view of the packaging container shown in FIG. 1;

FIG. 5 is a side view, taken from the left, of the packaging container shown in FIG. 1;

FIG. 6 is a side view, taken from the right, of the packaging container shown in FIG. 1;

FIG. 7 is a top view of the packaging container shown in FIG. 1;

FIG. 8 is a bottom view of the packaging container shown in FIG. 1;

FIG. 9 is a front and top perspective view of an alternate embodiment of the packaging container shown in FIG. 1;

FIG. 10 is a rear and bottom perspective view of the packaging container shown in FIG. 9;

FIG. 11 is a front view of the packaging container shown in FIG. 9;

FIG. 12 is a rear view of the packaging container shown in FIG. 9;

FIG. 13 is a side view, taken from the left, of the packaging container shown in FIG. 9;

FIG. 14 is a side view, taken from the right, of the packaging container shown in FIG. 9;

FIG. 15 is a top view of the packaging container shown in FIG. 9; and,

FIG. 16 is a bottom view of the packaging container shown in FIG. 9.
